FOLDER

Daniel B. Schwartzman, Jersey City, N. J.

Application November 25, 1938, Serial No. 242,339

6 Claims. (Cl. 206—7)

This invention relates to folders. It is particularly directed to a folder for lingerie, hosiery, underwear, blouses, or the like merchandise which is usually kept on shelves in a store and then placed on the counter for inspection by the customers, and the like articles.

An object of this invention is to provide a folder of the character described for protecting articles placed therein against dust and perspiring hands, and to keep said articles clean, and comprising a substantially rigid tray, board or bottom, and flexible, preferably transparent, flaps extending from the tray and adapted to be folded over articles on the tray, to cover the same, whereby the articles in the folder may be seen, and so that the flaps may be folded at any height to accommodate any height of pile on the tray.

A further object of this invention is to provide in a folder of the character described, a pair of opposite flaps having side flange portions extending at right angles to said flaps, and adapted to be overlapped by another pair of opposite flaps, to provide dust-proof corners at the four corners of the folder.

Yet another object of this invention is to provide in a folder of the character described, weighted means on a pair of opposite flaps adapted to hold the flaps down on the pile of articles on the tray, without necessity for fastening means.

A still further object of this invention is to provide a strong and durable article of the character described, which shall be relatively inexpensive to manufacture, easy to handle, attractive in appearance, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention,

Fig. 1 is a perspective view of a folder embodying the invention, with the flaps folded down over articles placed on the tray;

Fig. 2 is a cross-sectional view taken on line 2—2 of Fig. 1;

Fig. 3 is a cross-sectional view taken on line 3—3 of Fig. 1;

Fig. 4 is a top plan view of the folder, with a

pair of flaps in horizontal position, and another pair of flaps in vertical position;

Fig. 5 is a cross-sectional view taken on line 5—5 of Fig. 4;

Fig. 6 is a cross-sectional view of the weighted member on one of the flaps;

Fig. 7 is a view similar to Fig. 2, but illustrating a modified construction;

Fig. 8 is a partial, cross-sectional view taken on line 8—8 of Fig. 7; and

Fig. 9 is a reduced perspective view of the folder shown in Fig. 1.

Referring now in detail to the drawing, 10 designates a folder embodying the invention, for holding articles such as lingerie, hosiery, underwear, blouses, or the like merchandise which is usually placed on shelves and then put on the counter for display or inspection by the customer.

The folder 10 comprises a rigid or semi-rigid bottom, board or tray 11, preferably of rectangular shape and made of cardboard or the like material. Attached to the side edges of the board 11 are binding edges 12.

Stitched to the end edges of the board 11, as at 13, is a member 15, made of "Pliofilm" or the like transparent or translucent or colored film like material or other flexible, soft, sheet material. The member 15 has a central portion 16 disposed beneath the board 11 and flaps 17 extending from said central portion on opposite sides. The longitudinal edges of member 15 may be provided with binding edges 18. The stitching for the central portions of binding 18 serves to attach member 15 to the board 11, as at 13.

The outer ends of the flaps 17 are folded under, and stitched to the flaps, as at 20, to form longitudinal pockets 21 at the end of each flap. Within each pocket 21 is a weighted member 22, here shown for the purpose of illustration, in the form of a tubular flexible member 23 containing spaced metal balls 24, such as buckshot.

There is further stitched to the end edges of the board 11, a pair of similar, symmetrically disposed flaps 26. The flaps 26 are preferably likewise made of transparent flexible material, such as "Pliofilm" or other suitable flexible sheet material. Each flap 26 comprises a normally vertical wall 27 extending upwardly from an end edge of the board 11 and stitched thereto by line of stitching 13.

Extending from the portion 27 of each flap 26 are a pair of parallel side flange portions 28. The flange portions 28 of each member 26 extend toward the flange portions 28 of the other of said members. The flanges 28 decrease in

width toward the top, as shown in Fig. 5 of the drawing. The lower edges of the flanges 28 are stitched to the binding 12 at the side edges of the board 11.

5 It will now be understood that articles 30, such as lingerie, hosiery, underwear, blouses, or the like garments or merchandise may be placed in a pile on the board or tray 11. The flaps 26 may then be folded over the top of the articles 30 10 and into overlapping position. The flaps 17 may then be folded upwardly and inwardly over the folded flaps 26, the weighted means 22 serving to hold the flaps 17 down in position.

It will be noted that the flaps 17 and 26 may 15 be folded at any height to accommodate piles of various heights on the tray or board 11. The flaps 17 overlap the flange portions 28 of the flaps 26, forming dust-proof corners to keep the articles within the folder clean.

20 The flaps 26 may be provided with binding edges 26a if desired.

It will now be understood that the articles within the folder are completely visible because of the transparency of the flaps.

25 The article 10 is durable and clean because of the use of the binding tape at all edges of the flaps. The reinforced rigid bottom helps to maintain the articles placed thereon in flat condition. The portion 16 of the member 15 covers the 30 bottom of the board 11 to keep the board clean. The "Pliofilm" sheet may be washed.

35 In retail or department stores, where such articles as lingerie, hosiery, underwear, blouses, or the like merchandise are usually kept on shelves and then put on the counter for inspection by the customer, it has been found that such merchandise often becomes soiled because of dust and handling by perspiring hands. Such articles may be placed in the folder 10 and kept 40 clean and protected, without hindering the visibility of the articles due to packing.

In Figs. 7 and 8 there is shown a folder 10a, embodying the invention, and illustrating a modified construction. The folder 10a, likewise, has 45 a rigid or semi-rigid bottom, board or tray 40 of cardboard or the like material and of generally rectangular shape.

The board 40 is covered by sheets 41 and 42 50 of "Pliofilm" or the like transparent film like material at the top and bottom, and is provided with a pair of flaps 43 extending from one pair of opposite edges, and a pair of flaps 44 extending from the other pair of opposite edges. The flaps 43 are attached to the board 40 by binding edges 45, and the flaps 44 are attached to the board 40 by binding edges 46.

Attached to the side edges of the board 40, as 60 by the binding edges 45, are a pair of central straps 48 provided with complementary snap fasteners 49 for attaching the straps together in various adjusted positions. If desired the snap fasteners 49 may be omitted from the straps, and the straps made longer so that they 65 may be tied together.

The bottom board 11 or 40 may be made of wood, metal, composition or other suitable material, and the flaps may be attached thereto in any suitable manner.

70 The flaps of the folder are preferably made of a flexible rubber hydrochloride sheet film material, such as is known by the commercial name "Pliofilm." Such flaps are washable and will not crack upon being folded and unfolded, and 75 will not be affected materially by moisture in

the atmosphere. Such flaps are clean, transparent, and may be made in various colors.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all 10 matter herein set forth or shown in the accompanying drawing is to be interpreted as illustrative and not in a limiting sense.

Having thus described my invention, I claim as new and desire to secure by Letters Patent: 15

1. A folder of the character described, comprising a substantially rigid tray, a pair of flaps extending outwardly from the side edges of said tray, and a pair of flaps extending upwardly from the end edges of said tray, said second 20 pair of flaps each being provided with a pair of parallel side flange portions, the flange portions of one flap of said second pair of flaps extending toward the flange portions of the other flap of said second pair of flaps, and said flanges 25 extending substantially to the ends of said second pair of flaps.

2. A folder comprising a bottom tray on which articles may be placed, a plurality of pairs of oppositely extending, flexible flaps on said tray 30 adapted to be folded over articles placed on the tray, a pair of said oppositely extending flaps being provided with side extensions attached to the tray and overlapped by adjacent flaps, said flaps being made of transparent material, and 35 said side extensions extending substantially to the outer ends of the flaps from which they extend.

3. A folder comprising a substantially rigid bottom tray, a pair of oppositely extending flaps 40 on said tray, and a second pair of opposite flaps extending from said tray, and disposed between said first pair of flaps, said flaps being made of transparent flexible material, one pair of flaps being provided with flanges at the side edges 45 thereof adapted to be overlapped by the other pair of flaps, said flanges decreasing in width toward their outer ends, and extending substantially to the outer ends of the flaps from which they extend.

4. A folder comprising a substantially rigid flat member of rectangular shape, a transparent flexible sheet disposed beneath said member and having end portions extending beyond a pair of opposite edges of said member, whereby said 55 member is superimposed over the central portion of said sheet, the extending end portions of said sheet forming flaps adapted to be folded over the top of said member and being of such length as to overlap, said sheet being attached to said 60 member, and a pair of transparent flaps attached to the other pair of opposite edges of said member, and forming flaps adapted to be folded over the top of said member and being of such length as to overlap, said second pair of 65 flaps being formed with integral side flanges attached to first pair of opposite edges of the member and adapted to be overlapped by the extending portions of said sheet said side flanges extending at least for the major portion of the 70 flaps by which they are carried.

5. A folder for lingerie, hosiery, underwear, blouses, and the like articles, comprising a substantially rigid bottom tray on which said articles may be piled, a plurality of thin, flexible, 75

transparent, pairs of oppositely extending hydrochloride rubber flaps, attached to said bottom tray and extending therefrom, and adapted to be folded over the pile of articles on the tray, to cover the same, whereby the articles in the folder may be seen through the flaps, and whereby said flaps may be folded at any height to accommodate the pile on the tray, each pair of flaps being of such length as to overlap, a hydrochloride rubber sheet beneath said tray covering the underside thereof, and a hydrochloride rubber sheet covering the top surface of the tray.

6. A folder comprising a bottom tray on which articles may be placed, a plurality of pairs of oppositely extending flexible flaps on said tray, said flaps being of a length to overlap one another in operative position and adapted to be folded over articles placed on the tray, a pair of said oppositely extending flaps being provided with integral side flanges extending inwardly along the adjacent side of the tray and secured thereto, said side flanges extending at least for the major portion of the flaps by which they are carried.

DANIEL B. SCHWARTZMAN.
